WIRE DRAWING DRUM

George Woodward, West Orange, N. J., assignor
to Igoe Brothers, Newark, N. J.

Application November 22, 1935, Serial No. 50,998
Renewed January 4, 1938

1 Claim. (Cl. 205—20)

This invention relates to a wire drawing machine that accomplishes two or more successive drawings of the same wire in a continuous process and accomplishes this by substantially equalizing the tension on the wire throughout its drawn length.

The machines formerly employed for this purpose were expensive and unsatisfactory. The expense was caused by complicated mechanism such as differential gearing and other means of compensating for the speed of the wire as it is drawn by one drum on its first drawing and then drawn and coiled on the second drum. In order to secure uniformity of finish and size the tension of the wire is maintained by the present machine.

The invention is designed to provide an economical machine which requires no differential gearing since both drums can be rotated at the same speed at which the wire is moving which allows them to be driven on the same shaft. This economizes in space and power.

The manufacture of wire from bars leaves the wire with a scale which must be removed. The scale is removed after the pickling process by water under pressure and the wire is then allowed to stand and a green coating forms on the wire. The coating is washed off lightly and the wire is then put into a hot lime bath. The wire is then racked and dried. This leaves the wire with a thin coating that acts as a lubricant when the wire passes through the die. The present device by rotating the drums at a speed constant with the speed of the wire prevents any scraping of this coating and this in turn assists in the drawing due to the presence of the coating and, in consequence, the dies last longer and the drawing is easier and more satisfactory.

The invention also relates to certain details of construction which will be hereinafter more fully described.

The invention is illustrated in the accompanying drawing. Figure 1 is a diagrammatic view of my improved machine. Figure 2 is a side view of the two drawing drums with the lower part shown in section. Figure 3 is a bottom view of figure 2 with the bottom plate removed.

A diagrammatic view is presented in Figure 1, showing a die 10 which is the first die through which the wire passes and a second die 11 through which the wire is drawn a second time. The wire is drawn through the first die 10 by a drum 12 and is returned to the second die, usually over a pulley 13 and then drawn through the die 11 by the drum 14.

The wire passes around the drum 12 three or four turns and on the drum 14 it is coiled into the coil 15 for the proper length to provide the required size of coil and then removed as the product of the machine. The drums 12 and 14 rotate at the same speed and are usually secured together or to the same shaft 16.

The drum 14 is a convenient drum usually with a tapered periphery and of considerable height with a projecting apron 17 at the bottom. The top is open to permit the lifting and removal of the coil 15 of wire when the coil has reached the desired or predetermined weight.

The drum 12 is designed to include a slipping or lost-motion feature to slip in order to prevent the drum 12 passing along more wire to the second die than the drum 14 can take. This must be done without injury to the wire on the drum 12. The construction must be such that the wire engaging part of the drum 12 rotates at a speed that is the same as the speed of the wire in order that no scraping takes place to remove the coating from the wire.

The form of drum 12 is preferably made of a top plate 18 and a bottom plate 19 secured together, as by the screws 20. One of the plates has an annular flange or wall 21 extending to the other plate. Outside this wall is the slip ring 22 usually made up of sections 23 that are arc-shaped and normally slightly separated as at 24. This clearance allows the sections to move inwardly to a limited extent. The two plates 18 and 19 have opposed flanges 25 and 26 which confine the ring sections 23 against outward movement. If desired, I may place an annular backing 27 in the form of a ring or split ring, this backing being of material such as of asbestos, fibre, or the like or any resilient means that is compressible such as springs. This drum, with or without the ring 27, allows the sections 23 to move inwardly to slightly reduce the diameter of that part of the drum that receives the coil, that part being the periphery of the slip ring formed by the sections 23. The flanges 25 and 26, particularly the latter, act to prevent coating from the wire from working in behind the rings or segments 23. The presence of the coating on the inside face of the parts 23 causes them to bind and they will not slip on the wall 21. In order to prevent this and insure slipping of the parts under pressure the flanges, especially the flange 26 acts to ward off and collect the coating which does not enter behind the flange nor behind the split ring parts.

It will be evident that in the event of excess

drawing by the drum 12 the increased tension on the few laps of wire on the slip ring will cause the tension on the wire coming from the die 10 to be relaxed and no excess of wire will be fed to the die 11 or the drum 14 to cause any looping of the wire between these elements of the machine and the wire passing around with the drum 12 will not be subjected to any scraping to remove the coating.

10 I claim:—

A drum for wire-drawing machines compris-

ing a top plate and a bottom plate, one of said plates having an annular wall extending to the other plate, means for securing said plates together, a sectional slip-ring surrounding said wall, said ring having a recess on the bottom edge of its outer wall, a flange on the bottom plate and fitting said recess, a flange on the top plate overlapping the top edge of the ring, and a resilient medium between the wall and the ring.
